C. S. MCKENNEY

BOX TRUNK HOLDER FOR AUTOMOBILE RUNNING BOARDS

Filed May 14, 1927

INVENTOR.

C. S. M^{CK}ENNEY
Watson E. Coleman
ATTORNEY.

UNITED STATES PATENT OFFICE.

CHARLES S. MCKENNEY, OF PETERSBURG, VIRGINIA, ASSIGNOR TO SEWARD TRUNK AND BAG COMPANY, OF PETERSBURG, VIRGINIA, A CORPORATION OF VIRGINIA.

BOX-TRUNK HOLDER FOR AUTOMOBILE RUNNING BOARDS.

Application filed May 14, 1927. Serial No. 191,469.

The object of this invention is a simple, durable, and efficient construction of device for securely attaching to the running board of an automobile a box trunk or other article, the parts being so arranged that the trunk or the like may be very quickly clamped or fastened in place and as quickly removed when desired, while at the same time when in position it will be held very securely and without liability to rattle or become accidentally detached.

The invention consists in certain constructions, and arrangements of the parts that I shall hereinafter fully describe and claim, reference being had to the accompanying drawing, in which

Figure 1 is a perspective view of my invention in applied position.

Fig. 2 is an end view thereof with the running board in section, and

Fig. 3 is a fragmentary detail sectional view through the lower end of one of the clamps, hereinafter specifically described.

In the drawing, the numeral 10 designates the running board of an automobile, and 11 a box trunk or the like. The latter has secured to its ends, as shown, keepers 12 which, in the present instance, are made of strap iron with offset intermediate portions and 30 ends riveted or otherwise securely attached to the ends of the box trunk.

13 designates bowed clamps of which there are two in actual practice, and each clamp is provided at its upper inwardly projecting end and in the lower edge thereof, with a recess 14 designed to form a hook 15, this end being insertable through the intermediate or looped portion of an adjoining keeper 12, as clearly illustrated in the drawing.

The lower inwardly projecting end of each clamp 13 is twisted at right angles to the main body portion of the clamp and thence extended downward and rebent upon itself to form upper and lower members 16 and 17 of a nut holder in which a nut 18 is received; as shown, and these members 16 and 17 of a nut-holder are apertured for the passage through them of a screw-threaded binding post 20 which is provided at its lower end with a handle 21 of any desired construction or formation.

In assembling the parts it is obvious that the nuts 18 may be readily slipped in between the upper and lower members 16 and

17 of the nut-holders on the clamps, the screw-threaded binding posts 20 being then inserted through the apertures 19 and worked through the nuts.

In applying the device to the running board of an automobile, the upper hooked ends of the bowed clamps 13 are inserted inwardly into and through the keepers 12, the clamps being disposed in vertical planes and having their lower ends extended inward underneath the running board, the screw-threaded binding posts being then worked upward as is obvious and into engagement with the lower surface of the running board, whereupon by tightening up on the binding posts 20, the upper hook portions of the clamps will be drawn down into firm engagement with the keepers 12 and the box trunk 11 or the like will be securely and rigidly held in place upon the running board.

From the foregoing description, in connection with the accompanying drawing, it will be seen that I have provided a very simple and efficient device of this character which has comparatively few parts that may be very cheaply made and readily assembled, and that by means of the clamps and their keepers the box may be quickly secured in place and also quickly detached whenever desired.

While the accompanying drawing illustrates what I believe to be the preferred embodiment of my invention, it is to be understood that my invention is not limited thereto, and that various changes may be made in construction and arrangement and proportions of the parts without departing from the scope of the invention as claimed.

I claim:

1. Means for attaching a box trunk or the like to the running board of an automobile comprising keepers secured to the ends of the box trunk, bowed clamps designed to extend in vertical planes adjoining the ends of the box trunk both above and below the running board, and provided at their upper ends with hooks adapted to extend through said keepers, the lower ends of said clamps being returned upon themselves to form upper and lower portions of a nut-holder, said members being apertured, nuts received between the upper and lower members of said nut-holders, and screw-threaded binding posts passing upward through said apertured portions of the nut-holder and work-

ing through the nuts into engagement with the under surface of the running board, as and for the purpose set forth.

2. Means for attaching a box trunk or the like to the running board of an automobile, the same comprising keepers secured to the ends of the box trunk, bowed clamps provided at their upper ends and in the lower edges thereof with recesses forming hooks 10 and insertable through said keepers, the lower ends of said clamps being twisted at right angles to the main body portions of the clamps and returned upon themselves to form upper and lower members of a nut-

holder, said members being apertured, nuts 15 receivable between the upper and lower members of said nut holders, and screw-threaded binding posts working upwardly through said nuts and through the apertures of the nut-holders into engagement with the 20 lower surface of the running board, as and for the purpose set forth, the lower ends of said binding posts being provided with handles.

In testimony whereof I hereunto affix my 25 signature,

CHARLES S. McKENNEY
